CLOSET BOLT AND COVER NUT UNIT

Martin E. Ismert, Jr., 8817 Prospect,
Kansas City, Mo. 64132

Filed Nov. 12, 1968, Ser. No. 14,501

Term of patent 14 years

Int. Cl. D23—02

U.S. Cl. D23—71

FIG. 1 is a perspective view of a closet bolt and cover nut unit embodying my design.

FIG. 2 is a side elevational view thereof.

FIG. 3 is a side elevational view taken at 90° from that of FIG. 2.

FIG. 4 is a top view thereof.

FIG. 5 is a bottom view thereof.

FIG. 6 is a partial sectional view through the cover nut and bolt unit.

I claim:

The ornamental design for a closet bolt and cover nut unit, as shown and described.
